(Cl. D14—3)

To all whom it may concern:

Be it known that we, Adolph A. Wagner and Arnold J. Werner, citizens of the United States of America, respectively residing at Milwaukee, in the county of Milwaukee and State of Wisconsin, and Elm Grove, in the county of Waukesha and State of Wisconsin, have invented a new, original, and ornamental Design for a Boom, of which the following is a specification, reference being had to the accompanying drawings, forming part thereof.

In the drawings:

Fig. 1 is a perspective view of a boom incorporating our new design.

Fig. 2 is a plan view of the boom shown in Fig. 1.

Fig. 3 is a side elevation of the boom shown in Fig. 1.

Fig. 4 is a front end elevation of the boom shown in Fig. 1.

We claim:

The ornamental design for a boom, as shown.
